PIPE UNION

James Howard Williams, Lincoln, R. I., assignor to Grinnell Corporation, Providence, R. I., a corporation of Delaware

Application March 21, 1955, Serial No. 35,148

Term of patent 14 years

(Cl. D91—3)

FIG. 1

FIG. 2

FIG. 3

Figure 1 is an end elevational view of a pipe union embodying my new design;

Figure 2 is a side elevational view of the pipe union of Figure 1; and

Figure 3 is an enlarged sectional view through a portion of the pipe union taken substantially along the plane of line 3—3 of Figure 1.

The characteristic features of my design for a pipe union disclosed reside in the raised portions on the face of the outer polygonal member as shown in solid lines.

I claim:

The ornamental design for a pipe union, substantially as shown and described.
